United States Patent Office.

JOHN S. WOOD, OF HARTFORD, ASSIGNOR TO HIMSELF AND ELIZABETH P. SEYMOUR, OF WEST HARTFORD, CONNECTICUT.

Letters Patent No. 78,348, dated May 26, 1868.

IMPROVED BRICK-MACHINE.

The Schedule referred to in these Letters Patent and making part of the same.

TO ALL WHOM IT MAY CONCERN:

Be it known that I, JOHN S. WOOD, of Hartford, in the county of Hartford, and State of Connecticut, have invented a new and improved Brick-Machine; and I do hereby declare that the following is a full, clear, and exact description thereof, which will enable others skilled in the art to make and use the same, reference being had to the accompanying drawings, forming part of this specification.

Figure 1 represents a longitudinal vertical section of my improved brick-machine.

Figure 2 is a side elevation of the same.

Figure 3 is a detail longitudinal vertical section of the same.

Figure 4 is a detail side view of the same.

Similar letters of reference indicate corresponding parts.

This invention relates to certain improvements in brick-machines, by means of which the pressure upon the clay in the moulds can be regulated at will, by means of which the operation of the machine can be interrupted at once, whenever desired, without stopping the motion of the main driving-shaft, whereby the grate will be enabled to yield to stones or other obstacles that may project from the moulds, and whereby the gate in front of the mould-box will also be automatically raised by such obstructions.

The invention consists, first, in connecting an oscillating-lever, which is worked from the driving-shaft, with a rock-shaft, that operates the presser by means of a toothed or notched bar, in such a manner, that, by setting this bar, the degree of oscillation of the rock-shaft can be increased or reduced at will, or even entirely stopped, so that by this means the presser may be caused to compress the clay in the moulds more or less, or to remain entirely stationary, without in the least varying or stopping the motion of the driving-shaft.

The invention consists, second, in hinging the grate at its inner side, so that it may be raised in front by stones or other obstructions projecting from the sliding moulds, whereby the continued motion of the machine is permitted, even if such obstructions should accidentally have found their way into the moulds.

The invention, finally, consists in arranging, in combination with the hinged grate, a sliding gate, which rests with projecting pins or lugs upon the front of the grate, and which is therefore raised with and by the grate, to allow the discharge of the mould, with its projecting obstructions.

A, in the drawing, represents the frame of an ordinary or suitable brick-machine, in which a vertical shaft, B, carrying stirrers C C, has its bearings.

D represents the mould-box, arranged in front of the mud-mill E, and receiving the clay from the same through an aperture, a, in the front wall of the mud-mill.

F represents the reciprocating presser, arranged as cover of the mould-box, and suspended from a horizontal bar, b, which slides in slotted plates c c, that project from the ends of the stationary mould-box. By means of connecting-rods d d, the bar b is connected with cranks e e, which project from a horizontal rock-shaft, G, that has its bearings in the lower part of the frame A.

On the rock-shaft G is also arranged a crank, f, from the side of which a pin, g, projects, as shown in figs. 2 and 4. h is a bar, turning loose on the shaft G, and to its free end is pivoted a toothed or notched lever, H, as shown. On the shaft G turns also, loosely, a bar, i, which is at one end connected, by means of a rod, j, with a crank, K, projecting from a horizontal shaft, L, that receives rotary motion, by means of gearing or otherwise, from the driving-shaft B.

From the bar i project respectively, in front and rear of the shaft G, lugs l and m, which have bent-in or broadened ends. When the lever H is fitted upon the pin g, so that that pin fits into one of the notches in the lever, and when, then, the shaft B is rotated, the presser will be set in motion.

The rotation of the shaft B will impart an oscillating motion to the arm i, and the arm m on the same will therefore strike against the bar h, and as that is, by the lever H, locked to a crank on the shaft G, the said shaft will turn in one direction, and as, at the return move of the bar i, its lug l strikes against the front of the

bar *f*, the shaft *G* will be turned back. Thus oscillating motion will be imparted to the shaft *G*, and, thereby, reciprocating motion to the presser *F*. The degree of oscillation of the shaft *G* can be varied at will, by lengthening or shortening the connection of the crank, *f*, and bar *h*, which can be easily done, as the connecting-lever *H* is notched, and easily controllable. Thus, if the said connection is long, as in fig. 2, the oscillations will be considerable, and the presser will be moved far down, so as to compress the clay more than it would were the connection short, as in fig. 4.

By throwing the lever *H* quite off the pin *g*, the motion of the rock-shaft will be entirely stopped, while that of the shaft *B* need not be in the least interrupted.

J J are the moulds, operated by a follower, *L*, which can be set in motion by any suitable mechanism. The moulds pass below a grate, *M*, in the lower part of the mould-box *D*, and receive the clay from the mould-box through the apertures of the grate, and by the action of the presser.

The gate is, at its rear end, hinged to the frame of the machine, so that its front end is free to swing upward, as indicated in fig. 3. In this manner the moulds can pass out, even if obstructions project from them, as in fig. 8.

The front of the mould-box is closed by an up-and-down sliding gate, *N*, which rests by means of pins *n n*, upon the front of the grate, and which is consequently raised with the grate, in the manner shown in fig. 3. By means of a suitable lever, *O*, the grate *N* can be forced down again, after the obstructions have passed, and thereby the grate will also be forced down again into the original position, the pins *n* moving it down. The gate *N* may be secured in a swinging gate, *O*, as shown, or may constitute the only gate of the mould-box, as may be desired.

I claim as new, and desire to secure by Letters Patent—

1. The notched bar *H*, hinged to the loose arm *h* upon the shaft *G*, and serving to connect said arm with the crank, *f*, substantially as described, for the purpose specified.
2. The lever *i*, having lugs, *l m*, fitted loosely upon the rock-shaft *G*, and connected with the main driving-shaft, in combination with the loose arm *h*, crank, *f*, and hinged rack-bar *H*, for the purpose of giving motion to the rock-shaft *G*, substantially as described.
3. The swinging grate *M*, in combination with the sliding gate *N* and the pins *n*, all made and operating substantially as herein shown and described.

JOHN S. WOOD.
